THERMIONIC TUBE

Henry W. Parker, Toronto, Ontario, Canada, assignor to Rogers Radio Tubes Ltd., Toronto, Ontario, Canada, a corporation of Ontario, Canada

Application April 26, 1938, Serial No. 204,264

1 Claim. (Cl. 250—176)

My invention pertains to thermionic tubes and relates more especially to that type of such tubes employing screen grids and known as output power pentodes.

Output power pentodes as now constituted often exhibit a defect known as "blocking" when the tube is subjected to very strong signals entering the positive grid region.

It is well known that a high speed electron on hitting a solid substance splashes out other electrons known as secondary electrons which rebound with less velocity than the primary electrons and also that a primary electron can splash out several secondary electrons depending upon the work function of the surface upon which the primary electron impinges. With an oxide coated cathode the control grid due to contamination from the cathode has a very low work function surface and there is an effect, due to secondary emission from the grid, which causes a very low value of negative grid resistance in the positive grid region. This negative grid resistance or slope causes trouble when the grid is subjected to a strong signal before the cathode associated therewith is fully heated up. The cathodes of a power output tube heat up slower due to their greater mass than the cathodes of the preceding amplifier tubes in a plural stage amplifier so that often a strong signal is put on the power tube grid before the cathode thereof is heated up sufficiently. This swings the control grid of the power output tube into the positive grid region and once this region is entered the grid potential remains positive. Sometimes it is approximately one-half the anode potential and this high positive potential of the grid draws saturation current from the cathode which is limited only by emission from the cathode. Such high current overheats the tube, liberates gas and destroys the function of the tube. This occurrence is termed "blocking." The tube first overheats, causing the liberation of gas, and this liberation of gas causes loss of grid bias which causes increase of space current which may finally result in the destruction of the tube.

Several methods of overcoming this defect have been employed, such as graphitizing the control grid, oxidizing the grid, or utilizing a construction in which the grid rods of the control grid are of large diameter and placed relatively close to the cathode. All of these expedients have failed to give complete satisfaction. Some of them, while relieving the defect above referred to, have introduced other objectionable disadvantages.

One of the objects contemplated by my invention comprises producing a power output pentode which will not be subject to the above noted defect.

Another object contemplated by my invention comprises producing a power output pentode employing means in association with the control grid for presenting at all times during the operation of the tube a positive grid resistance to overcome the defects above noted.

A still further object comprises producing an output power pentode having simple and effective means for overcoming the defect above noted without introducing other undesirable electrical or mechanical effects.

I accomplish all of the above noted desirable results and others which will hereinafter become apparent by means of the novel construction, combination, arrangement and interaction of parts which will be hereafter more specifically described with reference to the accompanying drawing forming a part of this specification and in which like reference numerals designate corresponding parts throughout.

In the drawing:

Fig. 1 is a broken, partially sectioned enlarged view of my improved tube;

Fig. 2 is a sectional view of the same taken on the line 2—2 of Fig. 1; and

Fig. 3 is a set of curves showing the characteristics of a power output pentode employing my improvement.

Referring now especially to Figs. 1 and 2 which illustrate a power pentode incorporating my improvement, and with the usual base and contact prongs omitted, the envelope 4 which may be of metal but is preferably of glass or other vitreous material, supports the usual stem and press 5 which in turn support the electrodes. The anode 6 is supported by the usual standards and within the anode are supported the outer screen grid 7, inner screen grid 8, control grid 9 and indirectly heated cathode 10. The usual contact leads for the electrodes are shown in dotted line in the press and stem. The contact lead for the cathode includes the metallic support 15 and link 14, while the contact lead for the outer screen grid 7 includes the link 16. The usual metallic radiating vane 11 is welded to the control grid standards in order to reduce the temperature of the control grid to eliminate primary electron emission therefrom. My improvement comprises a small metallic target which may be termed a diode rectifier or diode target 12 and which in the embodiment illus-

trated is welded as shown in Fig. 2 to the wires of the control grid 9. It is thus maintained in relatively close proximity to the cathode 10. For purposes of clarity, only a few of the convolutions of the wires composing the screen grids 7 and 8 are shown.

The diode target, while shown in the form of a disc, may be a small square of nickel, molybdenum or other refractory metal and may be of any suitable size, shape or form. The area of the diode target should be of such dimensions that it will not interfere with the characteristics of the tube as far as plate transconductance and gain is concerned and for this reason the diameter or area of the diode disc is made rather small. If the area is made too large, it would interfere with gain characteristic of the tube, and if it is too small it would not function to present a positive grid resistance. The diode is placed close enough to the cathode and of such dimensions that the field of the anode is prevented from extending between the target and the cathode to influence the flow of electrons to the target and thus any secondary electrons return to the target instead of being drawn to the plate. Practically all of the secondary electrons derived from the target return to the target and hence there are always more electrons arriving at the grid to which the target is attached than are leaving the grid. Incrementally, this means that at no time will the grid have a negative slope but the derivative of the grid characteristic will always have a positive resistance value.

In power pentodes of the standard type incorporating my invention which I have constructed and successfully demonstrated, I have found that a nickel target of approximately $\frac{1}{8}$ " diameter united to the outside of control grid as shown in Figs. 1 and 2 operates very effectively to overcome the difficulty of "blocking" and yet does not interfere with any of the desired electrical characteristics of such tube. The diode target is in reality a separate entity from the grid and it could be a separate diode connected to the grid externally of the tube. Obviously, there is an optimum size for the target, not too large and not too small, which will present a positive grid resistance with minimum reduction in gain due to the projected area of the diode cutting down the effective area of the anode.

The operation of the diode target is shown in Fig. 3, in which curve 1 shows the diode target characteristics alone. This shows that there is presented a low positive resistance because the plate field cannot reach in behind and between the target and the cathode to influence secondary electrons from returning to the target. Curve 2 illustrates the grid wire characteristics alone,

while curve 3 represents an addition of curves 1 and 2 and illustrates the characteristics of the combined diode target electrically associated with the grid wire. In effect, this electrical association is a parallel connection. The region A in the curve is a positive grid region and extends normally to a value of about 20 volts. The region B is a positive region and extends normally from plus 20 volts to about one-half anode voltage, whereas the region C is a positive grid region and extends normally from about one-half anode voltage to full plate voltage. Referring to the curves it will be noted that the region B on curve 2 shows a negative slope. This negative slope is one reason for the difficulty known as "blocking" and when "blocking" occurs, the grid is thrown over into the region B. Once this region B is entered, the grid potential remains in the bottom of the "valley" indicated on curve 2 between the regions B and C. It happens that the grid potential in this region is approximately one-half of the plate potential and is positive and the grid will remain at a high positive value drawing saturation current from the cathode. As such current is limited only by the emission from the cathode this high current is sufficient to overheat the tube, liberate gas, and destroy the function of the tube, finally causing the destruction of the tube.

It will be apparent from the foregoing that my improved power pentode construction is completely effective in eliminating the difficulty known as "blocking"; that the means employed are simple and completely effective and that the means employed does not introduce any unwanted electrical or mechanical effects.

While I have thus illustrated and described one complete embodiment of my invention, it will be apparent that many changes can be made therein without departing from the intended scope and spirit of the invention. I do not therefore desire to limit myself to the foregoing except as may be pointed out in the appended claim in which I claim and desire to secure by United States Letters Patent the following:

A thermionic tube comprising, a substantially evacuated envelope enclosing a cathode, an anode, a control grid, and an additional electrode conductively connected to said control grid for neutralizing the effect of secondary emission from said control grid, said electrode comprising a small metallic target positioned adjacent one side only of said grid, between said cathode and said anode, in close proximity to said cathode and having a projected area considerably less than the total area of that side of said control grid to which it is adjacent.

HENRY W. PARKER.
